UNITED STATES PATENT OFFICE.

WILLIAM F. MORSE, OF ROCHESTER, NEW YORK, ASSIGNOR TO SAMUEL R. PARRY, OF ROCHESTER, NEW YORK.

MIXING-MACHINE.

1,267,578.

Specification of Letters Patent. Patented May 28, 1918.

Application filed March 19, 1917. Serial No. 155,900.

To all whom it may concern:

Be it known that I, WILLIAM F. MORSE, a citizen of the United States, residing at Rochester, in the county of Monroe and State of New York, have invented certain new and useful Improvements in Mixing-Machines, of which the following is a specification.

The object of this invention is to provide a new and improved form of mixing machine which is especially adapted to mix paste or other similar material.

This and other objects of the invention will be fully illustrated in the drawings, described in the specification and pointed out in the claims at the end thereof.

In the accompanying drawings,

Figure 1 is a side elevation of the mixing machine.

Fig. 2 is a top plan view of the base of the machine, the view being taken on the line 2^x—2^x of Fig. 1.

Fig. 3 is a vertical sectional view through the base of the machine, the section being taken on the line 3^x—3^x of Fig. 2.

Fig. 4 is a top plan view of the can and the mixing paddles provided therein, the view being taken on the line 4^x—4^x of Fig. 1.

Fig. 5 is a detail perspective view of a portion of the can and mixing paddles showing how the paddles are arranged and held in place therein.

Fig. 6 is a top plan view of a modified form of can and mixing paddle therefor.

Fig. 7 is a sectional view of another modified form of can and paddle therefor, the section being taken on the line 7^x—7^x of Fig. 8.

Fig. 8 is a longitudinal sectional view of the can shown in Fig. 7.

Fig. 9 shows a modified form of fastening the can to the turn table.

In the several figures of the drawings like reference numerals indicate like parts.

As illustrated in the drawings the machine is mounted on the base 1. This base is provided with the brackets 2 and 3 on one side thereof and has bolted thereto the bracket 4 on the opposite side thereof. The brackets 2, 3 and 4 are supported by suitable blocks 5 and 6 for the purpose of raising the base 1 to a predetermined height from the floor.

The base 1 as shown in Figs. 1 and 2 comprises a cylindrical casing which is closed at

the bottom and is open at the top. In the center of the bottom 7 of this casing is provided a lug 8 which projects into the casing and carries at the top thereof the center pin 9. This center pin has a shank 10 of reduced diameter which projects into the hollow center of the lug 8 and is held suspended therein by means of the shoulder 11 formed between the pin 9 and its shank 10. As shown in Figs. 2 and 3 suitable reinforcing ribs are provided on the inside of the casing, which ribs run radially on the bottom 7 of the casing from the wall 12 to the lug 8 in the center of the casing to increase the supporting strength of the lug 8.

On the inside of the wall 12 are provided the pockets 13, 14 and 15 in which are mounted to rotate the antifriction rollers 16, 17 and 18 respectively. Mounted to rotate on top of these rollers is the turn table 19 which comprises a circular plate 20 having an annular flange 21 projecting downwardly at its periphery thereof.

In the center of the turn table 19 and on its under side thereof is provided a lug 21. This lug has a cylindrical pocket 22 in the center thereof into which pocket projects the center pin 9. The turn table 19 is provided on its under side with a circular track 23 which rests on the antifriction rollers 16, 17 and 18 and by which the turn table 19 is supported on the base 1.

The turn table 19 is also provided on its under side with a circular rack 24 which meshes with the pinion 25. The pinion 25 is keyed to the end of the shaft 26, which shaft is mounted to rotate in the bearing 27 formed in the bracket 4, as shown in Fig. 3. Mounted on the outer end of the shaft 26 are the pulleys 28 and 29, the pulley 28 being keyed to the shaft 27 and the pulley 29 being mounted to rotate idly thereon. A belt (not shown) is used to drive these pulleys and may be shifted from one pulley to the other by means of the belt shifter 30. This belt shifter comprises a rod 31 which is mounted to slide in the bearing 32 and has keyed thereto suitably spaced apart the depending arms 33 and 34. These arms are adapted to straddle the belt and prevent its movement sidewise except when it is desired to shift the belt from one pulley to the other, in which case the arms 33 and 34 are moved to guide the belt onto the adjacent pulley.

The bearing 32 in which the rod 31 is

adapted to slide is formed on the upper end of the bracket 35. This bracket is supported on a sleeve 36 which in turn engages the reduced end 37 of the bracket 4. A set screw 38 passes through the sleeve 36 on its under side thereof and holds the sleeve rigidly in place on the end of the bracket 4.

The bracket 4 has a vertical extension 39 provided thereon at the end of which is formed the flange 40. A sleeve 41 having a flange 42 provided thereon is clamped on top of the flange 40 by means of the bolts 43 and rigidly supports the upright 44 on top of the extension 39 of the bracket 4, the upright 44 being fastened into the sleeve 41 to form an extension thereof. The upright 44 has an arm 45 clamped to the upper end thereof, which arm is provided with an adjustable sleeve 46. Passing through the sleeve and rigidly clamped in place therein is the pipe 47. This pipe has a reducing nipple 48 at the upper end thereof into which is fastened the pipe 49 which connects the T 50 with the pipe 47. A flexible hose 57 is connected 25 to the T 50 at right angles to the pipe 49 by means of the union coupling 58, which hose forms the steam inlet to the pipe 47. The adjacent opening of the T 50 is plugged up and is provided with an eye 51 into which 30 engages the hook 52 carried on the end of the cable 53. The cable 53 passes over suitable pulleys 54 and 55 and carries on the other end thereon a counter-weight 56 which is used for a purpose that will presently 35 appear.

The top surface of the turn table 19 has the lugs 59, 60 and 61 rigidly fastened thereto near the periphery thereof. The inner end of each of these lugs forms a groove 40 with the top surface of the turn table with which the rim 62 of the can 63 is adapted to engage. The lugs 60 and 61 are located slightly on one side of the center of the turn table in the direction toward the lug 59 to 45 allow the can 63 to be moved onto the top of the turn table until the rim 62 thereof engages the grooves formed by the lugs 59, 60 and 61. A small post 64 is then inserted into the opening 66 provided in the top surface of the turn table in front of the can. This post has a set screw 67 passing therethrough which can be adjusted to engage the reinforcing strip 68 fastened to the periphery of the can 63 as shown in Figs. 1 and 3. 50 In this manner the can 63 may be clamped between the lugs 59, 60 and 61 and the post 65 on the platform of the turn table and rigidly held in place thereon.

After the can 63 is fastened to the turn 60 table 19 in the manner above described the pipe 47 is inserted into the can 63 and is held stationary suspended therein by means of the clamping sleeve 46 as shown in Fig. 1. In this position the branch pipe which is 65 connected at right angles to the pipe 47 at

the lower end thereof is held suspended slightly above the bottom of the can 63 so that the steam which passes through the pipe 47 into the pipe 69 can escape into the mixture contained in the can through suitable openings 70 provided on the under side 70 of the pipe for a purpose that will presently appear.

Clamped to the pipe 47 above the branch pipe 69 and suitably spaced apart thereon 75 are the stationary mixing paddles 71, 72, 73 and 74. Each of these paddles comprises a pair of arms 75, having a section 76 of a sleeve provided on one end thereof. A lug 77 projects outwardly from each of the sections 76 in the opposite direction to its arm 75. The sleeve sections 76 of each pair of arms 75 embrace the pipe 47 and are arranged so that one of the arms projects to the right of the pipe and the other to the left thereof. Bolts 78 and 79 pass through the lugs 77 and inner end of the arms 75 on each side of the sleeve sections 76 respectively, and rigidly clamp each pair of sleeve sections in place on the pipe 47.

On the inside of the wall of the can 63 is fastened the bracket 80. This bracket has a hook 81 formed at the top thereof which engages the upper rim 82 of the can. A set screw 83 passes through the end of the hook 95 81 which is adapted to make engagement with the outside of the can below the rim 82 and clamp the bracket 80 in place thereon. To hold the bracket 80 firmly in place on the inside of the can 63 two pairs of lugs 84 and 100 85 are provided near the bottom and top of the can. Each of the lugs has an angular projection which forms a short channel with the wall of the can. Each pair of these channels formed by the lugs 84 and 85 respectively is adapted to receive the enlarged ends 86 and 87 of the bracket 80 and aid the set screw 83 in holding the bracket 80 rigidly in place on the inside of the can 63.

The bracket 80 has a series of arms 88, 89, 110 90 and 91 integral therewith and projecting at right angles thereto. These arms are suitably spaced apart so that they project into the spaces formed between the paddles 71, 72, 73 and 74 as shown in Fig. 5.

In Fig. 6 is shown a modified form of can 92 having ratchet like ridges formed on the wall of the can. The paddles 93 used in connection with this can are curved and are rigidly held in place on pipe 47 as shown in 120 this figure. This type of can and paddles may be used for special purposes where no rotating paddles are required.

Figs. 7 and 8 show still another type of can and mixing paddle therefor. The walls 125 of this can are corrugated as shown at 93A. The paddle 94 used in connection with this type of can comprises two pairs of arms 95 similar to the arms shown in Fig. 5 and numbered 72, 73, 74, and 75. The arms 95 130

are clamped to the pipe 47 in the manner described in connection with the arm 71, etc. and are suitably spaced apart. The outer end of each of the arms 95 is curved in such a manner that the arms on one side of the pipe curve in one direction and the arms on the other side curve in the opposite direction.

Fastened to these arms on each side of the pipe 47 is a blade 96 and 97 respectively. Each of these blades is provided with the slots 98 and 99 through which pass the clamping screws 100 by which these blades are clamped to the ends of the arms 95. The slots 98 and 99 permit an adjustment of the blades on the arms 95 so that they can be moved toward or away from the corrugated wall of the can.

When only the mixing paddles shown in Figs. 6, 7 and 8 are used the pipe 47 is closed at the end by means of the cap 101 as no steam is used when the machine is operated with any of these paddles. It will be understood, however, that steam may be used in connection with these paddles if desired.

The operation of the machine is as follows:

The ingredients for the paste are inserted into the can 63 which is then slid on top of the turn table 19 until the lower edge thereof engages the lugs 59, 60 and 61. The post 65 is then inserted into the opening 66 provided in the turn table and the set screw 67 mounted in the post 65 is screwed against the reinforcing strip 68 provided on the can 63 so as to firmly clamp the lower end of the can between the lugs 59, 60 and 61 and the post 65.

The pipe 47 with the paddles 71, 72, 73 and 74 clamped thereon may then be lowered into the inside of the can and properly held suspended therein as shown in Fig. 5. In this figure the paddles 71, 72, 73 and 74 project into the spaces provided between the paddles or arms 88, 89, 90 and 91 on the bracket 80 so that on the rotation of the can 63 to which the bracket is clamped the arms 88, 89, 90 and 91 do not strike the paddles 71, 72, 73 and 74.

Power is then applied to pulley 28 to rotate the shaft 27 and with it the pinion 25 keyed to the inner end thereof. The pinion 25 meshes with the circular rack 24 provided on the under side of the turn table 19 so that on the rotation of the pinion 25 the circular rack 24, and in turn the turn table 19, is rotated around the stationary center pin 9.

The antifriction rollers 16, 17 and 18, mounted to rotate in the base 1, support the turn table 19 and eliminate unnecessary friction between the turn table 19 and the base 1 and permit its easy rotation thereon. The can 63 clamped to the top of the turn table 19 rotates with the turn table so that the arms 88, 89, 90 and 91 revolve around the

pipe 47 and between the paddles 70, 71, 72 and 73, and thoroughly mix the ingredients contained in the can. The can is kept rotating until the paste is properly mixed and ready for use.

Either before or after or during the rotation of the can containing the ingredients of the paste, steam may be applied thereto to cook the contents of the can. This is done by admitting steam through the flexible hose 75 57 into the vertical pipe 47 and the cross pipe 69 from where it passes out into the paste in the can through the opening 70 provided in the cross pipe 69.

After the paste is properly mixed and 80 cooked by means of the mechanism above described, the clamping sleeve 46 is opened to allow the counter-weight 56 on the end of the cable 53 to pull the pipe 47 and its paddles 70, 71, 72 and 73 out of the can 63 and 85 permit the removal of the can from the turn table 19 to make room for another can which may have been prepared for mixing while the contents in the first can was mixed by the machine.

The bracket 80 with its arms 90, 91 and 92 is disconnected from the first can and may be inserted into the next can which is then ready to be clamped to the turn table and rotated in the manner above described.

When using the can and paddles shown in Figs. 6, 7 and 8 the paddles are so adjusted that the contents of the can is forced against the wall of the can. The rubbing action of the corrugated wall of the can thus gradually reduces the lump portions of the paste.

Instead of locking the can 63 on to the turn table 19 by means of the post 64 and the set screw 67 a pin 102 may be inserted into the opening 66 of the turn table. This 105 pin is adapted to make engagement with one of the wedge shaped lugs 103 which are fastened to the can 63 on either side thereof as shown in Fig. 9. When the turn table 19 is rotated in the direction of the arrow shown in this figure the pin 102 moves up the inclined end of the wedge-shaped lug 103 and gradually shifts and forces the lower end of the can against the lugs 59, 60 and 61 and clamps the edge 62 110 thereof between these lugs and the pin 103. To unlock the can 63 from the turn table 19 the can is given a short twist in the opposite direction from the arrow which disengages the pin 102 from the wedge-shaped 120 lug 103 and allows the easy removal of the pin 102 from the turn table.

I claim.

1. In a mixing machine the combination of a base, an upright mounted on said base, 125 an arm projecting from said upright, a rod mounted to slide on the end of said arm, paddles carried on the end of said rod, a turn table mounted to rotate on said base, said turn table being adapted to hold a can 130

rigidly in place thereon, said rod with said paddles being adapted to vertically slide in and out of said can or hold stationary suspended in said can.

5. 2. In a mixing machine the combination of a base, an upright mounted on said base, an arm carried on the end of said upright and at right angles thereto, a pipe mounted to slide in the end of said arm and parallel to said upright, a distributing pipe at the lower end of said pipe, an inlet provided at the upper end of said pipe, a turn table mounted to rotate on said base, a can mounted on said turn table, said distributing pipe being adapted to vertically slide in and out of said can and project into said can and held suspended therein.

10. 3. In a mixing machine the combination of a base, a turn table mounted to rotate on said base, a can adapted to be clamped to said turn table, a series of mixing paddles held stationary in the center of said can, a series of paddles clamped to the wall of said can, said stationary mixing paddles being adapted to pass between said mixing paddles in said can on the rotation thereof.

15. 4. In a mixing machine the combination of a hollow base, a series of pockets on the inside of the wall of said base, antifriction rollers mounted to rotate in said pockets and projecting above said base, a center pin mounted in said base, a turn table mounted to rotate on top of said antifriction rollers, the center of said turn table being adapted to engage said center pin to provide a pivot around which said turn table is adapted to revolve.

20. 5. In a mixing machine the combination of a hollow base, a series of pockets provided on the walls of said base, antifriction rollers mounted to rotate in said pockets and projecting above said base, a center pin mounted in said base, a turn table mounted to rotate on top of said antifriction rollers, the center of said turn table being adapted to engage said center pin to provide a pivot around which said turn table is adapted to revolve, a series of stationary lugs provided on top of said turn table and on one side thereof, a removable lug on the opposite side thereof, said removable lug being adapted to clamp the bottom of a can on top of said turn table.

25. 6. In a mixing machine the combination of a base, a pin mounted in the center of said base, antifriction rollers mounted to rotate near the periphery of said base and projecting above said base, a turn table engaging said center pin, said turn table being adapted to rotate on top of said antifriction rollers, a bracket mounted on said base, bearings provided in said bracket, a shaft mounted to rotate in said bearings, said shaft having a pinion keyed to the end thereof, a circular rack mounted on said

turn table, said pinion being adapted to mesh with the said circular rack and rotate said rack on the rotation of said shaft and means for driving said shaft.

7. In a mixing machine the combination of a base, a turn table mounted to rotate on said base, a can clamped to the top of said turn table, a bracket provided on said base, said bracket having a vertical extension, an upright mounted on said extension, an arm mounted on said upright, said arm being provided with a clamp, a rod mounted in said clamp and held vertically in place in said clamp, a counter-weight adapted to lift said rod when said clamp is released, paddles carried on the lower end of said rod, said rod and said paddles being adapted to project into a can rigidly mounted on said turn table, means for driving said turn table.

8. In a mixing machine the combination of a base, a turn table mounted to rotate on said base, a can clamped to the top of said turn table, a series of mixing paddles held stationary in the center of said can, each of said paddles comprising a pair of arms having a semicircular channel on one side thereof, means to clamp two of said semi-circular channels together and hold said arms in line with each other.

9. In a mixing machine the combination of a base, a turn table mounted to rotate on top of said base, a can being adapted to be clamped on top of said turn table, said can having a pair of lugs at the top and bottom of the inside of the wall, said lugs being in line with each other and being adapted to hold a bracket, said bracket carrying a series of arms projecting radially into said can.

10. In a mixing machine the combination of a base, a turn table mounted to rotate on top of said base, a can being adapted to be clamped on top of said turn table, a bracket having a hook formed at the top thereof adapted to engage the rim of said can, means on said hook to clamp the top of said bracket in place on the top of said can, said bracket projecting inside of said can, arms carried on said bracket and projecting radially into said can, a pair of lugs at the top and bottom of the inside of the wall of said can, said lugs being in line with each other and being adapted to hold the bracket projecting into said can.

11. In a mixing machine the combination of turn table, a can clamped on said turn table, an interchangeable bracket carried in said can, said bracket having an enlarged top and bottom, a pair of lugs fastened to the top and bottom of said can on the inside thereof, said enlarged top and bottom of said interchangeable bracket being adapted to engage with said pairs of lugs provided on the inside of said can.

12. In a mixing machine the combination of a base, a turn table mounted to rotate on said base, means for rotating said turn table, a bracket mounted on said base, an upright 5 mounted on said bracket, a horizontal arm carried on the end of said upright, said arm being adapted to have a vertical rod mounted to vertically slide therein, paddles mounted on the lower end of said rod, a can mounted 10 on said turn table and adapted to rotate therewith, said rod and said paddles being adapted to project into said can and held stationary therein, a counterweight attached to the opposite end of said rod to lift said 15 rod on the release thereof by said arm on said upright.

13. In a mixing machine, the combination of a base, a turn table mounted to rotate on said base, a can adapted to be clamped to 20 said turn table, a rod held stationary suspended in the center of said can, a series of mixing paddles clamped to said rod, each of said mixing paddles comprising a pair of arms having a semi-circular sleeve on the inner end thereof, said sleeves being adapted 25

to embrace said rod, means to clamp each of said pair of sleeves on said rod to hold said arms on said rod and in line with each other.

14. In a mixing machine, the combination 30 of a base, a turn table mounted to rotate on said base, a can adapted to be clamped to said turn table, a rod held stationary suspended in the center of said can, a series of mixing paddles clamped to said rod, each of 35 said mixing paddles comprising a pair of arms having a semi-circular sleeve on the inner end thereof, said sleeves being adapted to embrace said rod, means to clamp each of said pair of sleeves on said rod to hold said 40 arms on said rod and in line with each other, a series of paddles clamped to the wall of said can, said stationary paddles on said rod being adapted to pass between said mixing paddles in said can on the rotation thereof. 45

In testimony whereof I affix my signature in presence of a witness.

WILLIAM F. MORSE.
